UNITED STATES PATENT OFFICE.

JOSEPH T. BERTHELOTE, OF HAVRE, MONTANA.

BELL-MUFFLER.

1,295,261.

Specification of Letters Patent. Patented Feb. 25, 1919.

Application filed September 14, 1918. Serial No. 254,081.

To all whom it may concern:

Be it known that I, JOSEPH T. BERTHELOTE, a citizen of the United States, residing at Havre, in the county of Hill and State 5 of Montana, have invented new and useful Improvements in Bell-Mufflers, of which the following is a specification.

This invention has reference to means for muffling the sound of telephone bells.

10 The primary object of the invention is to produce a device of this character which shall be self-sustaining when arranged upon the bells, the same being provided with cushion elements that directly engage with the 15 bells to muffle or dampen the sound therefrom.

In carrying out my invention it is my purpose to produce a dampening or muffling device for telephone bells in the nature of a 20 spring frame, comprising an arched member having lateral extensions at the ends thereof, each of the latter being provided with inturned ears, and between these ears are pivotally secured segments of rubber or 25 other compressible material. The arched central portion of the frame normally forces the ends thereof toward each other. The inner ears are arranged inward of the 30 bells, and the compression or tension exerted by the arched member forces the compressible elements into contact with the bells, and consequently sustains the device in operative position without the employment of auxiliary fastening means.

35 I accomplish the foregoing objects, and others which will appear as the nature of the invention is better understood, by a construction, combination and operative arrangement of parts referred to in the following description and set forth in what 40 I claim.

In the drawings:

Figure 1 is a front elevation illustrating the application of the improvement;

45 Fig. 2 is a sectional view approximately on the line 2—2 of Fig. 1;

Fig. 3 is a sectional view approximately on the line 3—3 of Fig. 1; and

Fig. 4 is a perspective view of the improvement.

The advantages and desirability of muffling telephone bells is too well known to be set forth.

A portion of a telephone box is, in the 55 drawings, indicated by the numeral 5, the

bells thereon are indicated by the numerals 6, the striker for the bells by the numeral 7 and the arched protector for the striker by the numeral 8.

The improvement is in the nature of a 60 frame, comprising an arched central portion 9 having widened ends 10 which are bent angularly, in the same direction from the arch 9, providing the lateral ends of the frame. These ends, outward of the arch 9 65 have, upon their edges inwardly extending ears 11 and 12 respectively. The inner ears 12 are longer than the outer ears 11, and the pairs of ears are preferably disposed at an outward angle with respect to the arch 9. 70 Pivots secured between each pair of ears 11 and 12, as at 13 is a segment 14 of compressible material, rubber preferred, and the inner concaved surfaces 15 of the compressible elements 14 are so shaped as to engage with the periphery of the bells 6.

As stated, the frame is constructed of resilient material, and the arched portion 9 is designed to spring the ends 10 toward each other. The longer ears 12 being arranged inward of the bells will contact with the edges thereof, and the spring exerted by the arched member 9 will cause the compressible dampening or muffler members 14 to tightly engage with the bells, and as a 75 consequence soften the sound thereof and silence the noise caused by the vibration of the striker.

While the construction is illustrated in connection with two bells, it will be noted 80 that the central arched member of the frame will permit of the same being arranged on a single bell.

It is believed, from the foregoing description, when taken in connection with the 95 drawings that the simplicity of the construction and the advantages of the device will be perfectly apparent. It is to be stated, however, that while I have illustrated a satisfactory embodiment of the improvement 100 as it now appears to me, I may, at a later date desire to make changes therefrom, and therefore I am not to be restricted to the device as described and shown, but am entitled to all such modifications as fall within 105 the scope of what I claim.

Having thus described the invention, what is claimed as new, is:

1. In a device for the purpose set forth, a resilient frame including an arched cen- 110

tral portion having lateral ends, and compressible elements pivotally secured to said ends.

2. In a device for the purpose set forth, 5 a resilient frame including a central arched portion having lateral ends formed thereon, and compressible elements carried by said ends.

3. In a device for the purpose set forth, 10 10 a resilient frame including a central arched portion having lateral ends, and pivoted segments of compressible material on said ends.

4. In a device for the purpose set forth, 15 15 a resilient frame, including a central arched

portion having lateral ends, ears on the edges of said ends to the opposite sides of the arch, and a compressible element pivotally secured between each pair of ears.

5. In a device for the purpose set forth, 20 20 a resilient frame including a central arched portion having lateral ends arranged at an angle with respect thereto, ears on the edges of said ends to the opposite sides of the arch, the inner ears being of a greater 25 length than the outer ears, and a segment of compressible material arranged between each pair of ears and pivoted thereto.

In testimony whereof I affix my signature.
JOSEPH T. BERTHELOTE.
